UNITED STATES PATENT OFFICE.

JESSE JENNISON AND GEORGE H. HIGGINS, OF CORTLAND, NEW YORK.

SHEET-METAL BOW.

1,251,532.

Specification of Letters Patent.

Patented Jan. 1, 1918.

Application filed February 12, 1917. Serial No. 148,099.

To all whom it may concern:

Be it known that we, JESSE JENNISON and GEORGE H. HIGGINS, citizens of the United States, and residents of Cortland, in the county of Cortland, in the State of New York, have invented new and useful Improvements in Sheet-Metal Bows, of which the following, taken in connection with the accompanying drawings, is a full, clear, and exact description.

This invention relates to certain improvements in bows, and pertains specifically to a sheet metal tubular bow for use with bow sockets of tops for vehicles, such as automobiles, motor-boats, and the like.

An object of the invention is to produce a bow comprising a hollow steel tube, preferably of oval cross section, which may be made of predetermined uniform length and preferably somewhat tapered at its opposite ends and adapted to be further automatically tapered when assembled by driving fit with a bow socket. By this construction the use of bow-setting machines is avoided in assembling.

Further, the bow may be provided with a Japan enamel finish, thus permitting the omission of the usual fabric covering required with wooden bows.

Further, in the use of wooden bows ordinarily steamed and bent to required shape, variations in temperature and humidity deform the bows so that the uniform character and shape of the bows is lost and re-bending is necessary in assembling the bows and sockets, whereas the shape of the tubular metallic bows is permanent and uniform.

The tubular sheet metal bow is lighter and of greater strength for the same cross section as compared with wooden bows, and the oval shape of the bow permits the free and unobstructed passage of the links, arms and the like of "one man tops" without cutting away corners and projecting angular parts of wooden bows.

Other objects and advantages will appear from the following description, taken in connection with the accompanying drawings, in which—

Figure 1 is a side elevation of a bow of this invention assembled by a driving fit with a portion of a bow socket.

Fig. 2 is a front elevation of a portion of a bow socket so assembled, parts being shown in section.

Fig. 3 is a cross section on line 3—3, Fig. 1.

Fig. 4 is a cross section on line 4—4, Fig. 2.

Fig. 5 is a longitudinal section through the bow and a clamp for securing the bow to the top of a wind-shield illustrating the method of attaching the clamp to the bow.

Fig. 6 is a plan view of a complete bow showing one end of the bow fitted within the usual bow socket.

As shown, each bow —1— comprises a single strip of sheet metal bent in tubular form and preferably of oval cross section, the portions —2— and —3— of the strip being turned inwardly and diverging inwardly and having their edge portions —4— and —5—, respectively, provided with return-bent interlocked flanges forming a keystone channel extending longitudinally of the bow.

Within the channel is positioned a strip —6— of wood or suitable material, to which the fabric covering of the top, such as leather or the like, may be readily secured, the insert being of keystone conformation in cross section to fit the channel and permanently secure the wooden strip therein.

In the process of manufacture, the wooden strip may be drawn into the channel before the longitudinal bends are formed in the bow. The bow may then be bent longitudinally to desired form, the usual form being with its ends —7— extending substantially parallel and at approximately right angles to the body of the bow. The end portions —7— may then be compressed in any suitable manner to tapered form, contracting somewhat the keystone channel adjacent the ends of the bow and compressing the wooden insert to further assist in constituting the engagement between the insert and the bow of a permanent nature. The end of the bow is so shaped by driving fit as to tightly fit within the bow socket —8— of usual downwardly tapered form.

The bow may be driven into the socket until the frictional engagement renders their connection rigid, and automatically compressing and tapering the ends —7— of the bow.

When the flanged end portions —4— and —5— have been interlocked, they may be rolled in any suitable and usual manner to minimize the projection of these portions and to constitute the inner surface of the recess of substantially continuous even contour. It will be understood that the showing of these flanged portions shown in Figs.

3 and 4 is exaggerated as to these portions of the structure in order to illustrate clearly the interlocking engagement of the parts.

An important feature of this invention 5 sides in the method of securing a clamp or attachment to the bow by means of which the top can be secured to any stationary portion, as the wind-shield. The clamp —9— has a base portion —10— adapted to rest 10 against the inner surface of the bow.

Suitable openings or conduits are formed 15 in the wooden insert —6—, such openings extending through the inner wall of the channel formed of the parts —4— and —5—. The inner wall of the bow is formed with an 20 opening of greater diameter adapted to receive and permit the passage of a sleeve or ferrule —11—, the inner end of which is adapted to lie in contact with the inner wall of the keystone channel, while the outer end rests in contact with the base —10— of clamp —9—. Bolts —12— are then extended 25 through the openings in the wooden insert —6— and the inner wall of the keystone channel through the ferrules —11— and 30 registering openings in the base —10—. These bolts are adapted to receive nuts —13— by which the parts are drawn tightly together and the clamp rigidly secured to the bow.

It will be apparent that the ferrules —11— act to prevent any substantial deformation of the tubular bow by fixedly spacing the inner wall of the channel and the base of 35 the clamp —9—, forming a continuous rigid structure at the point of connection of the clamp.

It will also be apparent that the interlocked joint between the ends of the strip of 40 metal comprising the tube may be formed at any point along the tube, and, as shown is formed in the inner wall of the recess and should preferably be formed somewhere in the wall of the recess, although not, perhaps, as a portion of the inner wall.

By the words "solid tube" as used in the 45 claims hereof is meant a rigid complete tube preferably formed of a single strip of sheet metal, or its equivalent, by bending to desired form and having its longitudinal edges rigidly and permanently united or interlocked.

Although we have shown and described 55 one specific construction, form and method of assemblage of the parts, we do not desire to limit ourselves to the same except as specifically set forth in the claims hereto annexed, as many changes may be made in the details of form, construction and method 60 of assemblage without departing from the spirit of this invention as set forth in the appended claims.

Further, as shown in Fig. 1, the tube —1— may be formed with drawn or otherwise 65 produced projections —15— lying

over the adjacent edge of the wooden insert —6—. The bow is adapted for securement to the socket by means additional to the frictional engagement, such as forcing a punch through the contacting walls of the 70 parts to form interlocking burs.

What we claim is:

1. A **U** shaped bow formed of a rigid complete metallic tube having a longitudinal groove extending throughout its entire 75 length and interrupting the continuity of the exterior contour of the tube, a wooden insert secured in and substantially fitting the groove and exposed upon the outer face of the tube, the ends of the tube being contractible and adapted to be tapered by driving fit with the upper ends of tapered respective bow sockets to constitute a substantially rigid frictional engagement between the bow and the bow sockets, said complete metallic 80 tube formed of a strip of sheet metal having its longitudinal edges rigidly united to form a seam extending longitudinally of the bow.

2. A **U** shaped bow formed of a rigid complete metallic tube of oval cross section having its opposite ends adapted for insertion within and frictional engagement with opposite tubular bow sockets of tapered form, said metallic tubular bow having a longitudinal groove extending throughout substantially its entire length and interrupting the continuity of the exterior contour of the tube, a wooden insert secured in and substantially fitting the groove and exposed upon the outer face of the tube, said tube formed of a strip of sheet metal having its longitudinal edges rigidly and permanently united to form a seam extending longitudinally of the bow. 100

3. A **U** shaped bow formed of a rigid complete metallic tube of oval cross section having a longitudinal groove of inverted keystone shape extending throughout its entire 105 length and interrupting the continuity of the exterior contour of the tube, a wooden insert secured in and substantially fitting the groove and exposed upon the outer face of the tube, the ends of the tube being contractible and adapted to be tapered by driving fit with the upper ends of tapered respective bow sockets to constitute a substantially rigid frictional engagement between the bow and the bow sockets, said complete metallic 110 tube formed of a strip of sheet metal having its longitudinal edges rigidly united to form a seam in the wall of the keystone groove and extending longitudinally of the bow.

4. The combination with bow sockets having seats in their upper ends, of a **U**-shaped bow formed of a rigid complete metallic tube of oval cross section tapered at its opposite ends for engagement with said bow sockets, said tube having a longitudinal 120 125 130

groove extending throughout substantially its entire length and interrupting the continuity of the exterior contour of the tube, a wooden insert secured in and substantially fitting the groove and exposed upon the outer surface of the tube, said tube formed of a strip of sheet metal having its longitudinal edges rigidly and permanently united to form a seam extending longitudinally of the bow.

5 5. A tubular sheet metal bow having a longitudinal channel, a wooden insert in said channel, a conduit through the wooden insert and the inner wall of the channel, an 15 enlarged opening through the bow registering with said conduit, an attachment having a portion resting against the bow, a ferrule between the attachment and the inner wall of the channel, and a bolt extending through 20 said conduit, said ferrule and said attachment for securing the attachment to the bow.

6. A tubular sheet metal bow having a longitudinal channel, a wooden insert in the 25 channel, an attachment secured to the bow by means extending through the tubular sheet metal and the wooden insert, and means for bracing the channel wall against the attachment.

30 7. A tubular sheet metal bow having a

longitudinal channel, a wooden insert in the channel, an attachment secured to the bow by means extending through the tubular sheet metal and the wooden insert, and a sleeve within the bow and held in place by 35 said means and holding the channel wall in predetermined position relatively to the opposite wall of the bow.

8. The combination with bow sockets having tapered seats in their upper ends, of a 40 bow comprising a rigid, complete metallic tube tapered at its opposite ends for engagement with said bow sockets, said tube having a longitudinal groove of inverted key- 45 stone shape extending throughout substantially its entire length and interrupting the continuity of the exterior contour of the tube, and a wooden insert secured in and substantially fitting the groove and exposed upon the outer surface of the tube and forming a substantially symmetrical continuation of the exterior contour of the tube.

In witness whereof we have hereunto set our hands this 9th day of February, 1917.

JESSE JENNISON.
GEORGE H. HIGGINS.
